REFRIGERATOR CAR.

Application filed January 26, 1922. Serial No. 532,515.

This invention relates to improvements in refrigerator cars, and its purpose is to provide a more convenient and durable construction which will be more efficient in 5 operation.

The principal object of the invention is to provide an improved construction of the ice chamber of the car, in order to permit the ready cleaning thereof. Another object 10 is to provide improved means for mounting the sub-floor or ice platform of the refrigerant chamber. A further object is to provide an ice chamber having an ice platform composed of a plurality of removable sec- 15 tions. Other objects relate to various features of construction and arrangement which will more fully hereinafter appear.

The nature of the invention will be understood from the following specification, taken 20 in connection with the accompanying drawings, in which one embodiment is illustrated.

Figure 1 shows a vertical cross section of a refrigerator car embodying the present invention, the major portion of the section 25 being taken through the refrigerating chamber, while the remainder of the section is taken through the refrigerant chamber;

Fig. 2 shows a horizontal section, taken on the line 2-2 of Fig. 1 looking in the direction of the arrows, two of the sub-floor sections of the ice chamber being removed.

Fig. 3 is a vertical section, taken on the line 3-3 of Fig. 1 looking in the direction of the arrows.

Fig. 4 is an enlarged detail vertical section, taken on the line 4-4 of Fig. 1 looking in the direction of the arrows.

Fig. 5 is a detail horizontal section, taken on the line 5-5 of Fig. 4 looking in the direction of the arrows;

Fig. 6 is a perspective view of one of the brackets or castings by which the floor of the ice chamber and the transverse partitions between the ice chamber and the refrigerating chamber are supported; and

Fig. 7 is a perspective view of one of the removable sections of the ice chamber floor.

The invention relates to improvements in refrigerator cars of the usual type, in which 60 the interior space of the car is divided by two transverse partitions or bulkheads to form two ice or refrigerant chambers lo-

cated at the ends of the car. Inasmuch as the two ends of the car are alike, the construction of one only will be described 55 herein.

As illustrated in the drawings the invention is shown embodied in a refrigerator car comprising side sills 10, center sills 11, and intermediate sills 12, united by end sills 13 60 and other transverse sills 14. These sills support the lower floor boards 15, and a sheet metal plate 16 is mounted over the boards and extends throughout the area of the car. A layer of insulating material 17 is mounted 65

above the plate, and another sheet metal plate 18, of similar area, is mounted above the insulating layer. The boards which form the main car floor 20 are mounted on the sheet metal plate 18 and extend trans- 70

versely of the car, as shown, for example, in Fig. 3. The side walls 21 of the car extend vertically between the side sills 10 and the longitudinal side plates 22. These side walls comprise an outside sheathing 23 and inside 75

sheathing 24, between which is mounted a plurality of sheets of insulating material 25, such as a felt, or the like, these sheets being connected at their edges to the longitudinal frame members 10 and 22 and also to the lon- 80

gitudinal belt rails 26 and ribs 27. The roof 28 is supported by the side plates 22 and the ridge pole 29, and also by the trans- 85

verse carlines 30 which extend between the side plates. The inside roof sheathing 31 is mounted on the carlines, and a layer of insu- 90

lating material 32 is mounted above this roof sheathing with a sheet metal covering 33 thereover, as shown particularly in Fig. 1. The purlines 34 extend longitudinally of 95

the car above the sheet metal plate 33, and the roof boards 35 are supported by these purlines as well as by the ridge pole 29 and the side plates 22. Adjacent the ends of the car the usual hatchways 36 are formed through the roof, to permit the loading of the refrigerant chambers with ice. The end wall 38 extends vertically between the end sill 13 and the end plate 39 and comprises the outside sheathing 40 and the inside 100

sheathing 41, which are supported and spaced apart by horizontal belt rails 42 and ribs 43, thus forming the air chamber 44. A plurality of sheets of insulating material

45 are mounted in the end walls with their edges overlapping the belt rails and abutting against the ribs.

The inner region of the car is divided by 5 two transverse partitions or bulkheads 50, which extend vertically between the floor and the roof, thus dividing the car into a refrigerating chamber 51, adapted to contain perishable goods, and two refrigerant 10 chambers 52 located adjacent the ends of the car and adapted to receive the ice inserted through the hatchways 36.

The refrigerating chamber 51 has a sub-floor 53, formed by a plurality of transverse 15 cleats 54 resting on the longitudinal frame members 55, which are supported in turn by the floor 20. The end cleat 54^a of the sub-floor is hinged at 56, for a purpose hereinafter described. Within the refrigerant 20 chamber 52 the floor has a sheet metal covering 58, and a portion of the floor is removed to permit the depression of this sheet metal plate to form a transverse drain channel 59, having a drain trap 60 connected thereto and leading through the floor of the car adjacent each side wall, as shown in Figs. 2 and 3. These drain traps may be of the form described and claimed in my prior 25 Patent No. 1,329,015, granted January 27, 1920. The sheet metal covering 58 of the ice chamber floor is extended upwardly at the side walls of the car, as shown at 61, in contact with the inside sheathing, and a similar sheet metal plate 62 is extended upwardly 30 in contact with the inside sheathing 41 and the end wall of the car, thus forming a waterproof lining for the sides and end walls of the ice chamber. A plurality of vertical cleats 63 are secured to the end wall 35 38 in contact with the inner sheet metal lining 62, and a reticulated sheet metal plate 64 is secured to these cleats, thus forming a plurality of channels 65, through which the air can circulate around the ice in the refrigerant chamber.

A plurality of brackets 66, which may preferably be malleable castings, are secured to the floor and arranged to straddle the drain channel 59, shown in Fig. 3. These 40 brackets have the form illustrated particularly in Fig. 6, each comprising a lower base flange 66^a, having a vertical flange 66^b extending upwardly from the middle portion thereof and a transverse flange 66^c extending outwardly in opposite directions from the middle portion of the vertical flange and uniting it with the base flange. A horizontal flange 66^d extends longitudinally 45 from the transverse flanges 66^c and is formed integrally with the upper edge of one portion of the vertical flange 66^b. One end of the base flange 66^a is offset downwardly, as shown at 66^e, and these offset portions are united to the floor by bolts 67 passing 50 through the apertures 68. The other end of

the base flange and the opposite end of the vertical flange 66^b are formed integrally with the angular flange 66^f, which is adapted to engage and overlap the opposite edge of the drain channel, as shown in Fig. 3. These 55 brackets are adapted to support the bulkhead 50, which comprises a plurality of vertical posts 70 which rest at their lower ends on the base flanges 66^a of the brackets and seat against the vertical flanges 66^c, being slotted to receive the vertical flange 66^b. These posts are secured to the flanges 66^c 60 by bolts 71 and to the flanges 66^b by transversely extending bolts 72. All of the posts are further united by a transverse bar 73, which rests on the flanges 66^d and is secured to the posts by bolts 74. At their upper ends the posts 70 are secured by bolts 75 to brackets 76. These brackets are connected by bolts 77 to the roof boards and to a transverse frame member 78 which extends between the side plates 22.

The surface of the partition or bulkhead 50 toward the ice chamber 52 is formed by a reticulated sheet metal plate 80, which is secured to the posts 70 by a plurality of bolts 81, these bolts passing also through metal cleats 82, which extend vertically in contact with the outer surfaces of the plate 80, as shown particularly in Fig. 2. The opposite sides of the post, which are directed toward the refrigerating chamber 51 have the partition boards 83 secured thereto, and a plurality of layers of heat-insulating material 85 are mounted in contact with the boards 83 between the posts 70. Other retaining boards 86 seat against the inner surfaces of the layers of insulating material, and these boards are held in position by plates 87 which are secured to the latteral sides 100 of the posts 70. A galvanized sheet metal plate 88 is secured over the inner exposed surfaces of the posts 70, plates 87, and boards 86, thus forming a waterproof lining for the surface of the bulkhead which is directed 105 toward the ice chamber. A plurality of vertical air channels 89 are thus formed between the reticulated sheet metal plate 80 and the sheet metal plate 88, through which the air may circulate in proximity to the ice. The partition boards 83 and 86 and the associated water proof and heat-insulating construction terminate below the ceiling of the car, and a reticulated sheet metal plate or woven wire screen 90 is mounted 110 between the upper edges of the partition boards and the ceiling boards, thus permitting the warm air from the upper part of the refrigerating chamber to pass through the upper part of the bulkhead into the ice chamber and into the vertical air channels around the ice chamber. The partition boards 83 and 86 also terminate above the floor of the car, a single transverse cleat 91 being secured to the posts 70 below the lower 115 120 125 130

edges of the boards 83, thus forming openings 92 on opposite sides of the cleats 91 through which the cold air from the lower part of the ice chamber may pass outwardly 5 into the refrigerating chamber. This open construction in the lower part of the bulkhead also permits access to the drain channel 59 for the purpose of cleaning the same, and the facility of cleaning this channel is 10 increased by the hinged mounting of the board 54^a of the sub-floor, which may be moved upwardly out of its normal position.

A bar 93, similar to the bar 73, is secured to the end wall of the car in contact with the vertical ribs 63 by bolts 94. This bar is adapted to rest upon a plurality of brackets 95, each of which is located in alignment with one of the brackets 66. Each of these brackets has a horizontal upper flange 95^a 20 located in substantially the same plane with the horizontal flanges 66^a of the brackets 66 and with the upper surface of the sub-floor 54. A series of T-bars 96, each having a vertical stem 96^a and horizontal flanges 96^b, are supported by the brackets 66 and 95, the horizontal flanges 90^b of the T-bars being secured to the horizontal flanges 66^a and 95^a of the brackets by means of rivets 97. At the 25 sides of the ice chamber angle bars 98 are secured to the inside sheathing 24 and to the vertical cleats located within the inside sheathing of the car by means of bolts 99. The horizontal flanges 96^b of the T-bars and the horizontal flanges of the angle bars 98 are 30 adapted to form supports for a plurality of removable sub-floor sections 100, which form the ice platform within the refrigerant chamber. Each platform section is made up of a plurality of grate bars 101, each of 35 which is similar in contour to the stationary bars 73 and 93 which are secured to the bulkhead and to the end wall, respectively. These grate bars are spaced apart by a series of collars 102, and are united by longitudinal bolts 103 which extend through the grate bars and through the collars, as shown particularly in Fig. 7. When the platform sections are placed in position on the flanges of the T-bars and angle bars, their upper edges 40 lie in the same plane with the upper edges of the stationary bars 73 and 93, and the end bars 101 of the platform sections are spaced from these stationary bars by blocks 104, which are secured thereto by bolts 105.

The ice platform of the refrigerant chamber is thus made up of a plurality of removable sections which are located in proximity to the floor proper, designated by numeral 20, the brackets 66 and 95 having a comparatively small depth vertically, so that this construction is adapted to increase the capacity of the ice chamber by several hundred pounds as compared with the refrigerating cars heretofore used. This capacity is further increased by placing a waterproof gal-

vanized sheet metal lining at the sides of the ice chamber directly in contact with the inside sheathing of the car, thus eliminating vertical air channels at the sides of the ice chamber. The vertical air channels which are embodied in the end wall 38 and in the bulkhead 50 serve, in conjunction with the openings at the top and bottom of the bulkhead and the improved construction of the ice platform and the sub-floor, to provide an effective circulation of air within the car. The construction also permits ready access to the drain channel 59 and to the floor proper of the ice chamber, inasmuch as all of the platform sections may be readily removed. The car thus has unusual advantages in permitting ready cleaning of the floor of the ice chamber, drain channel, and drain pipes, which require frequent cleaning on account of the sediment deposited from the ice.

It will be noted that the frame member 78, by which the brackets 76 are supported, is mounted above the ceiling boards of the car, as shown particularly in Fig. 3, so that the flow of the warm air from the refrigerating chamber to the ice chamber is unobstructed in the region of the reticulated metal plates which form the upper part of the bulkhead 50. The current of air in contact with the ceiling boards thus flows freely into the ice chamber without the formation of eddies, and a much more perfect circulation of the air is obtained than is possible in the ordinary form of refrigerator car construction. The arrangement of the ice platform and the construction of the air circulating apertures through the lower part of the bulkhead also serves to permit a free flow of cold air from the lower part of the ice chamber to the refrigerating chamber, thus adding to the efficiency of the air-circulating system.

Although I have shown and described one form of the invention for purposes of illustration, it will be understood that it may be constructed in various other embodiments without departing from the scope of the appended claims.

I claim:

1. A refrigerator car comprising a refrigerant chamber, an ice platform comprising a plurality of complementary sections, and a member supporting said sections and extending between them to space them apart. 110

2. A refrigerator car comprising a refrigerant chamber, an ice platform in said chamber comprising a plurality of complementary sections, and supporting members for said sections extending longitudinally of said car 125 and projecting upwardly between adjacent sections.

3. A refrigerator car having a refrigerant chamber, an ice platform comprising a plurality of complementary sections, means 130

for supporting said sections and preventing movement thereof transversely of the car, and additional means for preventing movement of said sections on said supporting means longitudinally of the car.

4. A refrigerator car having a transverse bulkhead dividing it into refrigerating and refrigerant chambers, brackets mounted on the floor of said refrigerant chamber, a plurality of supporting members extending longitudinally of the car in said refrigerant chamber and resting on said brackets, and a plurality of ice platform sections spaced apart and supported by said supporting members.

5. A refrigerator car having a transverse bulkhead dividing it into refrigerating and refrigerant chambers, an ice platform supported in close proximity to the floor of said refrigerant chamber and comprising a plurality of sections each made up of a plurality of rails extending transversely of the car and spaced apart, and additional supplemental rails carried by said bulkhead and the end wall of the car with their upper edges in the plane of the upper edges of said first mentioned rails.

6. A refrigerator car comprising a refrigerant chamber, a plurality of T-bars mounted adjacent the floor of said chamber with their stems extending upwardly, and a plurality of removable ice platform sections supported on the flanges of said T-bars and separated by said stems.

35 7. A refrigerator car comprising a refrigerant chamber, a plurality of T-bars mounted adjacent the floor of said chamber with their stems extending upwardly, and a plurality of grate bars resting on the flanges of said T-bars.

40 8. A refrigerator car comprising a refrigerant chamber, a plurality of T-bars mounted adjacent the floor of said chamber with their stems extending upwardly, and a plurality of grate bars resting on the flanges of said T-bars, said grate bars being connected in groups with certain groups separated by said stems.

50 9. A refrigerator car having a refrigerant chamber, a plurality of T-bars extending longitudinally of the car in said refrigerant chamber adjacent the floor thereof, said T-bars having their stems directed upwardly, plates attached to the side walls of said car parallel to said T-bars, and ice platform sections removably supported on the flanges of said T-bars and plates.

60 10. A refrigerator car comprising a transverse bulkhead dividing the interior spaces thereof into refrigerant and refrigerating chambers, the floor of said refrigerant chamber having a transverse drain channel therein adjacent said bulkhead, the lower part of said bulkhead having apertures therein to permit access to said drain channel, and an

ice platform mounted in said refrigerant chamber adjacent the floor thereof, said ice platform comprising a plurality of removable sections adapted to permit access to the floor of said refrigerant chamber and to said drain channel.

70 11. A refrigerator car having a transverse drain channel in the floor thereof, a plurality of brackets mounted on said floor and extending over said drain channel, transverse bulkheads supported by said brackets, and an ice platform supported on said brackets and extending therefrom to the end wall of the car.

75 12. A refrigerator car having a transverse drain channel in the floor thereof, a plurality of brackets mounted on said floor and extending over said drain channel, transverse bulkheads supported by said brackets, a second series of brackets mounted on said floor adjacent the end wall of the car, and an ice platform mounted on said two series of brackets.

80 13. A refrigerator car having a transverse drain channel in the floor thereof, a plurality of brackets mounted on said floor and extending over said drain channel, transverse bulkheads supported by said brackets, a second series of brackets mounted on said floor adjacent the end wall of the car, a series of parallel supporting member mounted on oppositely disposed brackets, and a series of removable ice platform sections each mounted between and supported by two of said supporting members.

85 14. A refrigerator car having a transverse drain channel in the floor thereof, a plurality of brackets mounted on said floor and extending over said drain channel, transverse bulkheads supported by said brackets, a second series of brackets mounted on said floor adjacent the end wall of the car, a series of T-bars extending parallel to each other longitudinally of the car and supported at their ends by oppositely disposed brackets, said T-bars having their stems directed upwardly, plates secured to the side walls of said car parallel to said T-bars, and removable ice platform sections supported by the flanges of said T-bars and said plates.

90 15. The combination in a refrigerator car of a plurality of brackets mounted on the floor thereof, a series of posts each extending vertically from one of said brackets, a transverse frame member adjacent the upper part of the car, means for connecting the upper ends of said post to said frame member, and means carried by said post for forming a transverse partition wall for permitting the passage of air through the upper and lower parts of said wall.

95 16. The combination in a refrigerator car of a transverse frame member adjacent the roof of the car, ceiling boards extending beneath said frame member, vertical posts con-

nected to said frame member and extending downwardly therefrom, and means carried by said posts for forming a transverse partition wall and for permitting the unobstructed flow of air between said posts in contact with said ceiling boards.

17. In a refrigerator car, a series of vertical posts arranged transversely of the car, means for connecting said posts to the floor of the car, a transverse frame member extending across the upper part of said car, ceiling boards extending beneath said frame

member, brackets located on the under side of said ceiling boards and connected therethrough to said frame member, means for connecting each of said brackets through one of said posts, means attached to the intermediate part of said posts for forming a solid bulkhead, and means carried by the upper and lower part of said posts for permitting circulation of air therebetween. 15 20

In testimony whereof, I have subscribed my name.

EDWARD POSSON.
